UNITED STATES PATENT OFFICE.

WALTER T. OXLEY, OF FERGUS FALLS, MINNESOTA.

PHOTOGRAPHIC-PRINTING MACHINE.

1,124,795.

Specification of Letters Patent.

Patented Jan. 12, 1915.

Application filed May 13, 1909. Serial No. 495,641.

To all whom it may concern:

Be it known that I, WALTER T. OXLEY, a citizen of the United States, residing at Fergus Falls, in the county of Ottertail and State of Minnesota, have invented certain new and useful Improvements in Photographic-Printing Machines; and I do hereby declare the following to be a full, clear, and exact description of the invention, such as will enable others skilled in the art to which it appertains to make and use the same.

My invention has for its object to provide a simple and highly efficient photographic printing machine, and to this end, it consists of the novel devices and combinations of devices hereinafter described and defined in the claim.

In the accompanying drawings which illustrate the invention, like characters indicate like parts throughout the several views.

Referring to the drawings: Figure 1 is a plan view of the improved machine parts being broken away; Fig. 2 is a side elevation 25 of the same, some parts being broken away and some parts being sectioned; and Fig. 3 is a vertical section taken on the line $x^3 x^3$ of Fig. 1.

The numeral 1 indicates a rectangular box 30 or frame, which in front, is provided with a ground glass plate 2, and to the back of which is detachably applied a rectangular plate 3, having a rectangular opening 4 that is normally closed by a platen 5 of the trap 35 door type, and which is connected to said plate 3 at its lower edge by hinges 6. This plate 3 constitutes the body member of a printing frame, and has secured to its inner face, a rectangular marginal rim 7. The negative plate 8 is detachably clamped to the plate 3 by the usual rectangular clamping board 9, which is preferably detachably 40 connected to clips 10 on the rim 7 by a pivoted spring bar 11. The numeral 12 indicates a 45 pliable strips such as felt, applied to the opposing faces of the plate 3 and clamping board 9. The numeral 13 indicates a similar facing applied to the inner face of the platen 5. The platen 5 is provided with 50 an upwardly extended arm or operating handle 14, to the upper end of which a latch tripping finger 15 is shown as applied.

Preferably the printing frame is detachably secured to the box 1 by light metal 55 strips 16 secured to the bottom of the box, and provided with upturned ends for en-

gagement with the lower edge of the plate 3, and by a spring bar 17 secured to the top of said box provided with a perforation that engages a pin 18 on the upper edge of said 60 plate 3.

When the platen 5 and its operating handle 14 are moved from the position shown in Fig. 3 into the position shown in Fig. 2, the latch tripping finger 15 engages the long 65 lug 19 of an oscillatory latch 20, which latter is pivoted at 21 in the bearing 22 secured on the top of the box 1. The hub portion of the bearing latch 20 is provided with two notches 23 which are adapted to 70 be engaged by the beveled nose of a spring 24, which as shown, is secured within the bearing 22 and serves to quite firmly, but yieldingly hold the latch 20 in either of its two positions. When the latch 20 is moved 75 by engagement of the end of the tripping finger 15 with the lug 19 thereof as just above stated, a relatively short lug 25 thereof moves upward through a perforation 26 in said finger 15, so that when the hinged 80 platen 5 is moved into an open position, said latch 20 will be moved back to the position shown in Fig. 3. The said latch 20, as is evident, serves to automatically secure and yieldingly hold the platen in its closed 85 or operative position, with the card or paper to be printed pressed between said platen and the negative, but permits the platen to be moved into an open position when a little force is applied to the handle 14. 90

Normally the diffused light which passes into the box 1 through the ground plate 2 is cut off from the negative 18 by a pair of overlapped shutters 27. The upper shutter 27 is secured, at its upper edge, to a rock 95 shaft 28, and the lower shutter is secured at its lower edge to a rock shaft 29, both of which shafts are shown as mounted in recesses of a rectangular flange 30 secured within the box 1. Said shafts 28 and 29 100 project through one side of the box, and are provided outside of the box respectively with crank arms 31 and 32, the former of which extends rearward, and the latter of which extends forward. These two arms 105 31 and 32 are pivotally connected by a rod 33, and one of the said cranks to-wit, as shown, the lower crank 32 is also pivotally connected to the lower end of a rod 34, and it is further attached to the lower end of a 110 coiled spring 35, the upper end of which is attached to the box 1 and exerts a force

which normally holds the shutters 27 closed, as shown in Fig. 3.

The upper end of the connecting rod 34 is pivotally connected to the outer arm 36 of a rock shaft 37 mounted in suitable bearings 38 on top of the box 1. At its inner end, the shaft 37 is provided with an upwardly extended arm 39 to which the front end of a plunger or push rod 40 is pivotally attached. The rearwardly extended end of this plunger 40 rests loosely on, and is guided by the upper portion of the bearing 22, and normally its rear end stands in the position shown in Fig. 3, in which position it will be engaged by the operating handle 14, while the platen 5 is being moved from the position shown in Fig. 3 into its extreme closed position shown in Figs. 1 and 2.

The movement imparted to the plunger 40 by the final closing movement of the platen handle 14 oscillates the rock shaft 37, and through the arm and rod connections, moves the shutters 27 into open positions shown in Fig. 2, against the tension of the spring 35. This, of course, admits light through the negative to the card or printing paper which is then pressed by the platen against the negative. The shutters, as is evident, are automatically opened by the closing movement of the platen and they will be automatically closed by the spring 35 when the platen is given its initial movement toward an open position. In fact, the opening and closing of the shutters takes place while the platen is moving within the opening 4 of the back plate 3, and consequently while the said opening is subsequently closed against the passage of light.

The printing frame which includes the so-called back plate 3 need be removed only when the negative is to be changed. The

cards or paper on which the print is to be taken may be applied in position and printed in very rapid succession by simple movements of the hinged platen 5, which is, of course, accomplished by taking hold of the handle first, and oscillating the same. All other actions take place automatically as a result of movements of the platen.

In actual practice this improved photographic printing machine has been found highly efficient for the purposes had in view.

What I claim is:

In a photographic printing machine, the combination with a box, of a printing frame detachably secured to the back thereof, and provided with a hinged platen having an upwardly projecting operating handle, and means independent of the platen for holding the negative, said box having a light passage to the printing frame, a pair of yieldingly spring closed shutters normally closing the said light passage to said printing frame, and provided with crank arms outside of said box, a rod connecting the crank arms of said shutters, a rock shaft mounted on top of said box and provided with crank arms at its ends, a rod connecting the outer arm of said rock shaft to one of the shutter crank arms, and a plunger pivoted to the other arm of said rock shaft with its free end positioned to be engaged by the operating handle of said platen, and whereby said shutter will be opened when said platen is closed and will be closed when said platen is opened.

In testimony whereof I affix my signature in presence of two witnesses.

WALTER T. OXLEY.
